Primary Examiner — Jennifer Rivard(74) Attorney, Agent, or Firm — Jie Yang; ZanIP(57) CLAIM

The ornamental design for an electric nose hair trimmer, as shown and described.

DESCRIPTION

FIG. 1 is a perspective view of an electric nose hair trimmer, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrate the upper portion of the electric nose hair trimmer and form no part of the claimed design.

1 Claim, 6 Drawing Sheets(56)
